CARBURETOR

Harvey G. Ebert, Cranston, R. I.

Application July 8, 1932. Serial No. 621,339

9 Claims. (Cl. 261—47)

My present invention relates to improvements in spray carburetors for internal combustion engines.

It is the object of the present invention to provide a novel method and a novel apparatus for forming a complete and intimate intermixture of the fuel and air in the proper proportions for perfect combustion and accordingly secure a very high efficiency in the engine to which

10 the mixture is supplied.

To this end, the fuel is injected into the carburetor in a fine, thin stream, and the fuel particles are widely and uniformly separated and mixed with flowing air. These desirable effects 15 are obtained by injecting the fuel into the mixing chamber of the carburetor through a circumferential slot of very narrow width, thus projecting the fuel into the mixing chamber in the form of a thin film, and passing a rapidly whirling column of air of high velocity through the thin film to break up and atomize the fuel and produce a uniform diffusion of the atomized fuel particles in the air column.

Since a motor vehicle requires different fuel 25 and air proportions for different operating conditions, it is a further object of my invention to produce a uniform and controlled dilution of the fuel and air mixture at different engine speeds, thus resulting in greater economy. As the dilution should be uniform, and should be based on 30 the engine speed, the diluting air is admitted in the form of a sheet directed into and across the column of air and diffused vapor, and the volume of the diluting air is varied in correspondence 35 with the engine suction.

With the foregoing and related advantageous features in view, my invention consists of a novel method and a novel apparatus hereinafter more fully described, in conjunction with the accompanying drawings, and particularly pointed out in the claims appended hereto.

The accompanying drawings and the following description set forth in detail certain mechanisms for carrying out the invention, such mechanisms however being by way of example, and constituting a preferred arrangement suitable for the described purposes.

In the accompanying drawings, Fig. 1 is a sectional elevation of the preferred carburetor arrangement, the valves being shown in closed position;

Fig. 2 is a fragmentary sectional view, similar to Fig. 1, but showing the valves in open position;

Fig. 3 is a side elevation of the carburetor, 55 showing the valve linkage;

Fig. 4 is a section on the line 4—4 of Fig. 1;

Fig. 5 is an elevation of the float chamber, showing the position of the choke valve;

Fig. 6 is a section on the line 6—6 of Fig. 4;

Fig. 7 is an elevation of the central partition, 60 showing the rotation imparting vanes;

Fig. 8 is a diagrammatic development showing the blade positions of the air rotating mechanism;

Figs. 9 and 10 are perspective top and bottom 65 views of the upper plate, and Fig. 11 is a perspective view of the lower plate, forming the fuel injection mechanism.

Referring to the drawings, the novel carburetor 70 includes a float chamber 15, of standard construction, and a fuel and air mixer 16 which is preferably cast integral therewith. The float chamber has a float 17 of usual type, pivotally mounted in the float chamber, as at 18, and equipped with a needle valve 19 positioned in a valve chamber 20 and movable upon movement 75 of the float to cooperate with a valve seat 21 and thus control passage of fuel from the inlet passage 22 to the float chamber. The lower portion of the casting is formed with an air inlet passage 23, controlled by a choke valve 24 of standard type.

The mixer 16 includes a mixing chamber 25 in which the fuel and the main air mix, and into which the secondary or diluting air is conveyed. 85 As shown in Fig. 1, the mixer includes a lower portion 26 in which a whirl imparting member 27 is mounted, an intermediate portion consisting of two plates 28, 29 which form the fuel feed arrangement, and an upper portion 30 which forms 90 the outlet passageway for the gas and air mixtures.

The member 27 communicates with the air inlet 23, and has a central cylindrical partition 31 which separates the inflowing air into primary 95 air and diluting air, the latter passing through the central passageway 32 of the member 27 and the primary air passing through the outer passageway 33, where it encounters the arcuate vanes 34 which impart a whirl to the primary air and increase its speed, as the width between the vanes at the upper portion, indicated at *a* in Fig. 8, is less than the width between the vanes at the lower portion, indicated at *b* in Fig. 8. 100

The flow of diluting air is controlled by a conical type disk valve 35, see Figs. 1 and 2, which cooperates with the correspondingly shaped upper end 36 of the partition 31; the valve stem 37 terminates in a piston or plunger 38, housed 105 110

in a plunger chamber 39 and having its lower face exposed to the engine suction, a spring 40 between the plunger and a stationary spider normally keeping the valve seated and the plunger in down position. A cam 41 is mounted within the upper portion 30 for engagement with the upper face of the valve 35, and is manually controlled by movement of the throttle to release the valve for upward movement in response to engine speed.

The fuel flow is best described with reference to Figs. 1, 4 and 6; the fuel from the float chamber enters an inlet chamber 42 in the mixer, and passes upwardly through channels 43, 44 to chambers 45, 46 for the main fuel and the idling fuel flows respectively, the flow through these chambers being controlled by manually adjustable needle valves 47, 48. The main fuel supply passes to a downflow channel 49 which communicates with an annular chamber 50 formed in the upper plate 28, the latter in turn communicating with a main feed chamber 51 formed in the intermediate portion of the mixer between the two plates 28, 29, by means of a plurality of communicating ducts 52. The two plates are spaced apart at their inner edges to provide an annular fuel outlet 53, the width of this outlet being small, and preferably about three thousandths of an inch.

The chamber 46 communicates with the flow region above and below the throttle 55 through outlet channels 54 and 54^a, thus providing mixture for idling through passage 54 consisting of fuel from chamber 46 and air through channel 54^a; as the throttle opens, the two channels carry fuel from the chamber 46, thus compensating for the slight suction loss resulting from opening of the throttle. The throttle 55 and the cam 41 are interlinked, as shown in Fig. 3, by a novel linkage which includes two levers 56, 57 respectively keyed to the cam and the throttle shaft, and an intermediate link 58, the throttle shaft having the usual manually operable lever 59 secured to the other end thereof. The choke valve 24 is operated by a lever 60 keyed to the valve shaft and operable by the driver in the usual manner.

The operation of the improved carburetor may now be explained. In starting, the choke valve is closed in the usual manner, and then opened. The fuel flows into the annular chamber 51 and emerges in the form of a very thin sheet, and is impacted by the rapidly whirling ascending primary air to produce a uniform atomizing and dispersion of the fuel in the whirling air. As the mixture ascends, the valve 35 opens in accordance with the rate of engine speed, and the diluting air is forced outwardly as a conical sheet across the ascending column of mixture, thus ensuring a thorough and uniform dilution of the mixture.

It will be noted that the primary air is compressed in the whirl imparting member to increase its speed, and that the mixture first expands in the upper portion 30, and is then compressed prior to passage into the engine manifold. This expansion and compression increase the dispersion of the atomized fuel particles, the thermal changes in the air due to its initial compression and its subsequent expansion and compression assisting in the atomization. The resulting mixture has been found to be substantially perfect and to give complete combustion, without local ignition or other knock producing characteristics.

The above described carburetor construction utilizes up-draft, but may be readily redesigned

to utilize down-draft, if desired, without changing the fundamental principles of the invention.

The carburetor parts have been designed to be rugged and not easily put out of order, to make each part readily accessible, and to render assembly and dismantling simple and expeditious, the necessary tools for complete assembly, repair and adjustment being a wrench and screw driver.

While I have described a specific constructional embodiment of a carburetor for carrying out my invention, it is obvious that such changes in the general arrangement of the parts, and in their relative size and proportions, may be made as appear desirable for specific internal combustion engines, within the spirit and the scope of my invention as disclosed in the appended claims.

I claim:—

1. In a carburetor for an internal combustion engine, a mixing chamber, means for feeding fuel into said chamber in the form of a sheet transversely of the chamber, means for feeding air into said chamber in the form of a whirling column through said sheet, and means for feeding diluting air into said chamber in the form of a thin sheet across said column after it has mixed with the fuel. 95

2. In a carburetor for an internal combustion engine, a mixing chamber, means for feeding fuel into said chamber in the form of a sheet transversely of the chamber, means for feeding air into said chamber in the form of a whirling column through said sheet, and means for feeding diluting air in accordance with rate of engine speed into said chamber in the form of a thin sheet across said column after it has mixed with the fuel. 105

3. In a carburetor for an internal combustion engine, a mixer, a float chamber having a float control therein, an air inlet for said mixer, a fuel inlet for said float chamber, a mixing chamber in said mixer, an air passageway communicating with said air inlet with said mixing chamber, whirl imparting means in said air passageway, an annular fuel chamber in said mixer about said air passageway and communicating with said float chamber, and an annular radial slit communicating said annular fuel chamber with said air passageway. 115

4. In a carburetor for an internal combustion engine, a mixer, a float chamber having a float control therein, an air inlet for said mixer, a fuel inlet for said float chamber, a mixing chamber in said mixer, a primary air passageway and a secondary air passageway communicating said air inlet with said mixing chamber, whirl imparting means in said primary air passageway, an annular fuel chamber in said mixer about said primary air passageway and communicating with said float chamber, an annular radial slit in the wall of said mixer communicating said annular fuel chamber with said air passageway, and a valve in said secondary primary air passageway for controlling flow of the secondary air to the mixing chamber. 125

5. In a carburetor for an internal combustion engine, a mixer, a float chamber having a float control therein, an air inlet for said mixer, a fuel inlet for said float chamber, a mixing chamber in said mixer, a primary air passageway and a secondary air passageway communicating said air inlet with said mixing chamber, whirl imparting means in said primary air passageway, an annular radial slit in the wall of said mixer about said primary air passageway and communicating said annular fuel chamber with said primary 145
